UNITED STATES PATENT OFFICE.

NELSON GRAY, OF LOUISVILLE, KENTUCKY.

FOLDING CAR-STEP.

SPECIFICATION forming part of Letters Patent No. 728,097, dated May 12, 1903.

Application filed February 4, 1903. Serial No. 141,790. (No model.)

To all whom it may concern:

Be it known that I, NELSON GRAY, a citizen of the United States, and a resident of Louisville, in the county of Jefferson and State of Kentucky, have made certain new and useful Improvements in Folding Car-Steps, of which the following is a specification:

My invention is an improvement in car-steps, and has for an object a novel construction and combination of parts whereby the folding car-step may, together with the vestibule-door, entirely close the outer side of the vestibule when the folding step-section is closed and by which the folding step-section may be closed through the aid of a trap-door forming an extension of the car-platform when properly adjusted, as presently described; and the invention consists in certain novel constructions and combinations of parts, as will be hereinafter described and claimed.

In the drawings, Figure 1 is a perspective view, partly broken away and partly in section, of the car-step embodying my invention.

Fig. 2 is a vertical section in the direction of length of the car on about line 2 2 of Fig. 4. Fig. 3 is a cross-section of the step, showing the folding step-section opened for use and the vestibule-door and trap-door also opened, while Fig. 4 is a view similar to Fig. 3, except that the folding step-section is closed and the vestibule-door and trap-door are also closed.

Referring to Fig. 1, the car A has the platform B, the fixed step-section C, and the vestibule-door D, the latter being hinged at D', so it may be opened to the position shown in Fig. 3 or closed to the position shown in Fig. 4. The trap-door E is hinged at E' and may be opened to rest against the end of the car A or be closed to the position shown in Figs. 2 and 4, in which it will form a continuation of the platform B, as will be understood from Figs. 1 and 2 of the drawings. When the trap-door E is opened and the vestibule-door D is also opened, such door D will overlie the trap-door, and its fastenings may operate to secure the trap-door E in open upright position, as will be understood from Fig. 3 of the drawings. As shown in Figs. 1, 3, and 4, the vestibule-door D extends at its lower end below the plane of the platform B and trap-door E, so that it co-operates with the tread of the

folding step-section in closing the outer end of the steps when the parts are adjusted as shown in Fig. 4, and at the same time overlies the pivot and upper portion of the operating-rocker, presently described, when the folding car-step is adjusted to position for use, as shown in Fig. 3. The folding step-section F has the tread F' and the riser F² 6c and is braced when lowered to position for use by the bracket G. (See Figs. 3 and 4.) The step-section F is provided with the crank extension or arm H, which extends in position for engagement by one end I' of a rocker I, which rocker is pivoted at i and is connected by a link J with the trap-door E, so the movement of the trap-door from open to closed position may move the rocker in such manner as to cause the latter to operate the folding step-section. As shown and preferred, the rocker I is in the form of a bell-crank lever, one arm of which provides the end I' for engagement with the crank extension of the folding step-section, while its other arm connects with the link J, as shown in the drawings.

In the operation of my invention it will be noticed that when the parts are in the position shown in Fig. 4 the trap-door operates to hold the folding step-section in closed position and also operates as a means to resist any inward movement of the vestibule-door D. If now it is desired to use the steps, it is only necessary to raise the trap-door from the position shown in Figs. 2 and 4 to a vertical position, when the step-section F will automatically adjust from the position shown in Fig. 4 to that shown in Fig. 3, when the vestibule-door may be opened and the steps and other parts will be as shown in Fig. 3 and in position for use in entering or leaving the car.

It will be understood from Fig. 4 that the vestibule is entirely closed when the folding step-section and vestibule-door are closed, so that snow and the like cannot enter the steps, and there is no danger of the parts becoming frozen in position.

The free end of the arm I' may be provided with a roller i', as shown in Figs. 1, 3, and 4, to engage the arm H and relieve friction in the operation of the device.

Having thus described my invention, what

I claim as new, and desire to secure by Letters Patent, is—

1. The combination of the vestibule-door, the fixed platform-section, the trap-door arranged when closed to form an extension of the fixed platform-section and for adjustment when open behind the open vestibule-door, the fixed step-section, the folding step-section having a crank extension or arm, the bell-crank having one arm arranged to engage with the crank extension or arm of the folding step-section and a link connecting the trap-door with the other arm of the bell-crank lever substantially as set forth.
- 15 2. In an apparatus substantially as described the combination of the fixed step-section, the folding step-section, the trap-door arranged when closed to cover the space above said steps, the rocker between the trap-door and the folding step-section and arranged to operate the latter, and means whereby the trap-door may operate the rocker substantially as set forth.
- 20 3. The combination of the fixed step-section, the folding step-section having a crank extension or arm, the bell-crank lever having

one arm arranged to engage the crank extension of the folding step-section, the trap-door, and the link connecting the other arm of the bell-crank lever with the trap-door 30 substantially as set forth.

4. The combination of the fixed step-section, the platform, the trap-door, the vestibule-door projecting at its lower end below the plane of the trap-door and the folding 35 step-section having its tread arranged to operate with the vestibule-door in closing the outer end of the steps when the vestibule-door is closed substantially as set forth.

5. The combination with the platform and 40 the fixed step-section of the trap-door, the vestibule-door, and the folding step-section, and a rocker arranged between the trap-door and folding step-section and arranged to operate the folding step-section and a link connecting the rocker with the platform whereby 45 it may be operated by the movement of the platform substantially as set forth.
